- ings of the window to be used as a means of egress or escape from a prison or other enclosure. The openings 21 of the alternate rows of light openings are provided with panes 23 of wire frosted 5 glass which are adapted to admit the desired amount of light through the window and at the same time prevent persons on the interior from looking out and those on the exterior from looking into a prison.
- 10 Each of the ventilating openings of each row is provided with a copper wire screen 24 having a marginal frame 25 secured to the vertical and horizontal angle bars forming the ventilating openings. The screen is provided at its outer 15 face with a series of inclined slats 26 preferably constructed of copper and extending downwardly and outwardly from the screen and provided at their upper edges with attaching portions 27 suitably secured to the screen. The slats extend 20 entirely across the ventilating openings and are arranged in vertical overlapping relation, the lower edge of each slat being located below the plane of the upper edge of the next lower slat, with exception of the bottom slat which has its 25 lower edge extending to a point below the upper edge of the adjacent horizontal angle iron. This arrangement of the slats in overlapping relation forms a sight shield and prevents anyone from looking out or looking in through the window 30 when the ventilators 28 are open. The angle irons forming the rectangular light and ventilating openings are preferably T-shaped in cross section, as shown in the drawings, to form seats for the panes of wire frosted glass and the screens.
- 35 Each of the alternate rows of ventilating openings is provided with one of the ventilators 28 which consists of an oblong metal frame 29 and a continuous plate or pane 30 of wire across the glass.
- 40 The ventilator which is hinged at the bottom is preferably connected at the lower edge with the sash frame by butt hinges 31, but any other suitable form of hinge connection may, of course, be employed and the ventilator 28 is adapted to 45 swing outwardly and downwardly from the full line position illustrated in Fig. 3 of the drawings to the dotted line position to permit ventilation through the screen ventilating openings of the window. When the ventilator is open and in an inclined position it will prevent a person at the inner side of the window from looking downwardly and viewing the exterior of a prison and at the same time, it will prevent persons on the outside from looking upwardly through the spaces 50 between the inclined slats so that communication between persons inside and outside of a prison window will be effectually prevented and visual signaling of any character is eliminated. Drip 55 from rain or any other source of moisture is prevented from entering the window through the ventilating openings by a horizontal strip 32 located above and extending across each ventilating opening and secured to the angle or T-bars 20 preferably below the panes of wire frosted glass, as clearly illustrated in Fig. 3 of the drawings.
- 60 The hinged ventilators are provided at their upper edges at their ends with outwardly extending arms 33 suitably secured to the metal frames of the ventilators and extending outwardly therefrom horizontally when the ventilators are closed. The arms 33 are connected by pivots 34 to spaced tie bars 35 which are connected at their upper ends at the top of the window by a transverse connecting rod 36 provided with set screw 65
- collars 37 located at opposite sides of the tie bars through which the connecting rod passes. The connecting rod also passes through a vertical slot 38 of an arm 39 depending from a slidable ventilator operating rod 40 mounted in a guide opening 41 of a hanger 42 welded or otherwise secured to the top of the window frame and depending therefrom, as clearly illustrated in Figs. 2 and 3 of the drawings. The hanger 42 preferably consists of a piece of angle iron or T-bar, 10 but it may be of any other desired construction. The slidable ventilator operating rod is designed to extend to a prison gallery or other remote point of control and the depending arm 39 is preferably provided at its upper ends with a 15 sleeve 43 secured on the outer end of the rod 40 by a pin 44 or other suitable fastening device. The connecting rod which passes through the slot 38 is provided at opposite sides of the arm 39 with set screw collars 45. When the operating 20 rod is moved outwardly the ventilators are swung downwardly and outwardly to open the ventilators, which are simultaneously operated by the sliding movement of the operating rod. In practice a plurality of operating rods will be simultaneously actuated, each rod being connected with an arm 46 of a rock shaft 47 provided with an operating arm 48 and adapted to be locked in its adjustment by a ball and ratchet device 49 or other suitable means. 25
- 30 The rock shaft 47 and the locking means constitute a remote control device which may be arranged at any convenient point and which will be associated with a series of windows so that ventilators of a plurality of windows will be simultaneously operated and locked in open or closed position.
- 35 Should it be desired to increase the lighting capacity of the window the fixed inclined slats which form the sight shield at the screens may be provided with plates or panes of frosted glass or any other suitable material for permitting a predetermined amount of light to pass through the screen.
- 40 What is claimed is:
1. A window of the class described including a sash frame having a ventilating opening, a screen for the said opening secured to the sash frame, and a series of stationary inclined slats secured to and projecting from the screen and arranged at intervals in vertical overlapping relation and forming a sight shield covering the area of the ventilating opening. 45
  2. A window of the class described including a sash frame having a ventilating opening, a screen secured to the sash frame and covering the ventilating opening, stationary inclined slats secured to and extending outwardly from the screen and arranged in vertical overlapping relation to form a sight shield to prevent direct view through the ventilator opening, and a hinged imperforate ventilator member located exteriorly of the slats and covering the ventilating opening and forming a closure for the same with said slats confined between the screen and the ventilator member when the latter is closed and adapted to swing outwardly away from the screen and slats to permit ventilation through the ventilating opening. 55
  3. A window of the class described including a sash frame having a ventilating opening, a screen secured to the sash frame and covering the ventilating opening, stationary inclined slats extending outwardly from the screen and arranged in vertical overlapping relation to form 60
- 65
- 70
- 75

a sight shield to prevent direct view through the ventilator opening, and a hinged ventilator member located exteriorly of the slats and covering the ventilating opening and forming a closure for the same and when closed confining the slats between the same and the screen, said ventilator being composed of a frame and a frosted pane secured within the frame.

4. A window of the character described including a sash frame provided with a transverse row of relatively small side by side ventilation openings, separate screens secured to the sash frame in the openings thereof, a series of fixed inclined slats arranged in each relatively small ventilation opening and extending outwardly from the screen thereof and arranged in overlapping relation to form a sight shield, and a relatively long transverse ventilator hinged to the sash frame and extending across and covering the row of ventilation openings and movable outwardly to permit ventilation through the said openings.

5. A window of the character described including a sash frame provided with a transverse row of relatively small side by side ventilation openings, separate screens secured to the sash frame in the openings thereof, a series of fixed inclined slats arranged in each ventilation opening and extending outwardly from the screen thereof and arranged in overlapping relation to form a sight shield, and a relatively long transverse ventilator fitted against the sash frame and covering the row of ventilation openings and hinged at its bottom to the sash frame and adapted to swing downwardly and outwardly to permit ventilation through the ventilation openings to form a shield to prevent visual signaling through the window and when closed assuming vertical position in parallelism with said separate screens with said slats confined closely between the same and the screens.

6. A window of the character described including a sash frame having transverse rows of ventilation openings and transverse rows of light openings and provided in the light openings with panes, screens secured in the ventilation openings, sight shields secured to and located on the screens exteriorly thereof, and imperforate transverse ventilators hinged to the sash frame and forming closures for the rows of ventilation openings, and means connected with the ventilators for simultaneously opening and closing the same, and the ventilators when closed assuming parallelism with the respective screens and confining the sight shields between the same and the screens.

55 7. A window of the character described including a sash frame provided with alternate rows of light and ventilation openings, panes secured in

the light openings, screens mounted in the ventilation openings, transverse ventilators fitted against the sash frame and forming closures for the rows of ventilation openings and hinged at their lower edges to the sash frame to swing outwardly and downwardly, and operating means connected with the ventilators for opening and closing the same and for limiting the inward and downward movement of said closures to an upward inclined position on downward swinging movement thereof so as to prevent a view through the ventilation openings either from the front or the rear of the window.

8. A window of the character described including a sash frame provided with alternate rows of light and ventilation openings, panes secured in the light openings, screens mounted in the ventilation openings, transverse ventilators fitted against the sash frame and forming closures for the ventilation openings and hinged at their lower edges to the sash frame to swing outwardly and downwardly, arms extending outwardly from the ventilators at the upper edges thereof, and means connected to the arms which extend from the upper edges of the ventilators for simultaneously opening and closing the same.

9. A window of the character described including a sash frame provided with alternate rows of light and ventilation openings, panes secured in the light openings, screens mounted in the ventilation openings, sight shields secured to and located on the screens exteriorly thereof, transverse ventilators fitted against the sash frame and forming closures for the rows of ventilation openings and hinged to the sash frame to swing outwardly and downwardly, arms mounted on the ventilators at the upper edges thereof and located at the ends of the same, and means connected with the ventilators for simultaneously opening and closing the same and the ventilators when closed assuming parallelism with the respective screens and confining the sight shields between the same and the screens.

10. A window of the character described including a sash frame provided with vertical and horizontal T-bars forming alternate rows of light and ventilation openings and providing seats within the said openings, panes secured on the seats in the light openings, screens mounted on the seats in the ventilation openings, and strips extending across the ventilating openings and located above the ventilation openings and secured on the seats of the light openings and projecting outwardly from the T-bars to prevent moisture from entering the window through the ventilating openings.

RAYMOND L. CLARK.
